UNITED STATES PATENT OFFICE.

JACKSON WALTER FOSTER, OF JACKSONVILLE, FLORIDA.

HEATING DEVICE.

SPECIFICATION forming part of Letters Patent No. 677,969, dated July 9, 1901.

Application filed February 18, 1901. Serial No. 47,829. (No model.)

To all whom it may concern:

Be it known that I, JACKSON WALTER FOSTER, a citizen of the United States, residing at Jacksonville, in the county of Duval and

5 State of Florida, have invented a new and useful Heating Device, of which the following is a specification.

This invention relates to heating devices for heating the interior of buildings, and has 10 for its object to provide improved means for collecting and utilizing the heat and products of combustion that ordinarily escape directly from the stove or furnace to the chimney. It is furthermore designed to provide the device 15 in the nature of a heating-drum, which is arranged for convenient connection with a chimney, so as to receive the heat and products of combustion and finally discharge the same into the chimney after the heating capacity thereof has been partly or wholly exhausted, and, finally, to arrange for conveniently controlling the device, so as to shut off 20 the heat therefrom whenever desired.

With these and other objects in view the 25 present invention consists in the combination and arrangement of parts, as will be herein-after more fully described, shown in the accompanying drawings, and particularly pointed out in the appended claims, it being understood that changes in the form, proportion, size, and minor details may be made 30 within the scope of the claims without departing from the spirit or sacrificing any of the advantages of the invention.

35 In the drawings, Figure 1 is a central longitudinal sectional view taken through the present device applied to a chimney. Fig. 2 is a sectional view taken on the line 2 2 of Fig. 1. Fig. 3 is a transverse sectional view 40 taken on the line 3 3 of Fig. 1. Fig. 4 is a similar view on the line 4 4 of Fig. 1. Figs. 5, 6, and 7 are detail longitudinal sectional views of modified forms of the heating-drum.

Like characters of reference designate corresponding parts in all of the figures of the drawings.

Referring at first more particularly to Figs. 1 to 5, inclusive, it will be seen that the present device comprises a drum 1, formed by a 50 continuous pipe-coil, which is provided with an elbow 2, that is designed to be fitted into the usual stovepipe-opening of a chimney 3,

so that the ascending heat and products of combustion may pass into the heating-drum, and thereby heat the interior of the room 55 within which the drum may be placed.

In order that the heat may pass into the drum and then be conveyed back into the chimney in a continuous current, there is provided a partition 4, located centrally within 60 the elbow and extending for the entire length thereof, the front end of the partition being flush with the outer end of the elbow or pipe-section 2 and the inner end of the partition fitting against the inner wall of the drum or 65 coil at the inner end of said pipe-section. By this arrangement a current of heat may pass inwardly beneath the partition, thence through the coil or drum, and finally out over the top of the partition, as indicated by the 70 arrows.

To control the passage of the heat, there is provided a damper-plate 5, slidably mounted upon either side of the partition, but preferably upon the upper side thereof, and designed to be pushed forwardly into the chimney and against the opposite wall thereof, as 75 shown in Fig. 2 of the drawings. For the manipulation of this damper there is provided a push-rod 6, connected to the inner end thereof and projected slidably outward through an opening in the outer side of the elbow or pipe-section 2 and provided with an outer terminal handle 7, whereby the damper may be conveniently controlled. It will of course be 80 understood that the plate is of a width to readily enter the pipe when it is desired to have the chimney-flue unobstructed. The opposite duplicate foldable damper members 8 are hinged to the respective side edges of 85 the body portion 5, so as to be thrown outwardly in opposite directions into the plane of the body portion and completely close the chimney-flue in substantially the plane of the partition or the upper side of the inlet into 90 the heating-drum, whereby the heat and products of combustion are compelled to enter the drum and finally escape into the chimney-flue 95 above the damper and through the discharge-passage formed between the partition and the upper side of the pipe-section 2. Each wing or foldable damper member is hinged to the body-plate by means of corresponding bearing eyes or sleeves 9 and 10, formed upon the

adjacent edges of the wing and the plate, there being a pivot-pin 11 (shown in Fig. 3) passed through the corresponding sleeves.

When the damper is to be drawn within the 5 inlet-passage of the drum, so as to permit of the heat passing directly upwardly through the chimney-flue, the damper-wings are folded inwardly in opposite directions upon the body, as shown in Fig. 3, so as to reduce the width 10 of the damper to the width of the body-plate. To facilitate the folding of the wings, each of the latter is provided with a rotatable rod 12, located within the pipe and having a lateral 15 terminal extension or arm 13 connected to the adjacent wing, the opposite end of the rod being projected outwardly through the outer side of the drum and provided with a suitable handle 14, whereby the rod may be rotated or rocked to open and close the adjustment 20 damper-wing. The intermediate portion of each rod is mounted in a suitable bearing 15 upon the adjacent portion of the inner side of the inlet-pipe.

From the foregoing description it will be 25 apparent that the present device may be fitted in the ordinary stovepipe-opening of a chimney without altering the latter in any manner whatsoever, so as to collect and employ the commonly lost heat and products of 30 combustion to heat a room by radiation from the drum. Ordinarily the drum is comparatively small, so as to take up no more room than an ordinary heating-stove, and where the stovepipe-opening is adjacent to the ceiling 35 the drum may or may not reach to a point adjacent the floor of the room.

It will of course be understood that the size of the drums may vary and the shape or design thereof may be changed—as, for instance, as shown in Fig. 5, the coil or body 40 of the drum may be substantially circular instead of rectangular, as shown in Fig. 1, while in Fig. 6 a straight or direct inlet-pipe is employed, the principle being the same in 45 all of the forms. In Fig. 7 the drum is formed by a straight pipe having the intermediate partition which terminates short of the outer end of the pipe, so as to form a continuous 50 passage for the heat, the outer end of the pipe or drum being closed by means of a removable cap or closure 16, through which the damper-rods pass, the closure being removable to facilitate cleaning the interior of the drum.

55 What is claimed is—

1. A heating device of the character described, having an inlet, and an outlet, a slideable damper for the inlet, a foldable damper member hinged to the body of the damper, 60 and externally-accessible means for manipulating the body of the damper and for folding the foldable member thereof.

2. A heating device of the character described, having an inlet, and an outlet, both 65 of which are constructed for connection with a chimney, a slideable damper for the inlet and

constructed to be projected externally of the inlet and into a chimney, opposite foldable damper members hinged to respective edges of the body of the damper, and externally- 70 accessible means for sliding the damper in opposite directions and for folding and unfolding the foldable members.

3. A heating device of the character described, having an inlet, and an outlet, both 75 of which are constructed for connection with a chimney-flue, a slideable damper mounted to slide within the device and to be projected externally thereof into a chimney-flue between the inlet and the outlet, a push-rod 80 connected to the damper and projected slidably outward through a wall of the device, opposite foldable damper members hinged to respective side edges of the damper-body and constructed to close the chimney-flue, and rotatable rods connected to the respective foldable damper members, and projected externally of the device for folding and unfolding the foldable members.

4. A heating device of the character described, comprising a drum, having an inlet, and an outlet, which are constructed for connection with a chimney-flue, a slideable damper mounted within the device, located between the inlet and outlet, and constructed 95 to be projected externally and into the chimney-flue, opposite foldable damper members hinged to respective side edges of the damper-body, and constructed to fold inwardly in opposite directions upon the damper-body 100 and within the width thereof, and externally-accessible means for sliding the damper in opposite directions and for folding and unfolding the hinged damper members.

5. A heating device of the character described comprising a closed drum, having a branch pipe in connection with the interior thereof, constructed for connection with a chimney-flue, and provided with an intermediate longitudinal partition dividing the pipe 105 into a lower inlet-passage, and an upper outlet-passage, and a damper slidably mounted upon the partition for movement in opposite directions longitudinally upon the same, normally located entirely within the pipe, 110 and constructed to be projected outwardly through the outer open end of the pipe and form a continuation of the partition to close a chimney-flue.

6. A heating device of the character described, having a branch pipe, which is open at its outer end, and also provided with an intermediate longitudinal partition dividing the pipe into an inlet-passage, and an outlet-passage, and a slideable damper mounted within the pipe and upon the partition, said damper being located entirely within the pipe 125 when not in use and projected at the open end thereof when in use to direct the heat into the inlet-passage, externally-accessible 130 means for sliding the damper, opposite foldable damper members hinged to respective

side edges of the body and foldable inwardly in opposite directions upon the body and within the width thereof, and rotatable rods connected to the respective foldable members and projected externally of the device for manipulation of said members.

5 In testimony that I claim the foregoing as

my own I have hereto affixed my signature in the presence of two witnesses.

JACKSON WALTER FOSTER.
